United States Patent Office

Des. 186,345
Patented Oct. 13, 1959

186,345

DEEP FAT FRYER OR SIMILAR ARTICLE

Phillip M. Pappas, Houston, Tex.

Application May 3, 1957, Serial No. 46,013

Term of patent 14 years

(Cl. D81—10)

Fig. 1

Fig. 2

Fig. 1 is a perspective view of a deep fat fryer embodying my new design and showing the front and one side thereof, the opposite side being a mirror image of the side shown; and

Fig. 2 is a fragmentary top plan view illustrating the top rear thereof.

I claim:

The ornamental design for a deep fat fryer, or similar article, as shown and described.
